United States Patent Office

Des. 188,479
Patented July 26, 1960

188,479

APPLICATOR COMB

Joseph Lloyd Chiariello, 430 Orange St., Oakland, Calif.

Filed Feb. 10, 1960, Ser. No. 59,329

Term of patent 14 years

(Cl. D86—8)

Fig. 1 is a front elevational view of an applicator comb showing my new design;

Fig. 2 is a top plan view;

Fig. 3 is a bottom plan view;

Fig. 4 is a left end elevational view;

Fig. 5 is a right end elevational view;

Fig. 6 is a sectional view on line 6—6 of Fig. 1; and

Fig. 7 is a sectional view on line 7—7 of Fig. 1.

The teeth on the comb are coextensive with the dotted line illustration as shown in Figs. 1 and 2.

I claim:

The ornamental design for an applicator comb, as shown and described.
